BUMPER JACK

Frank L. Curran, St. Paul, Minn.

Application December 2, 1935, Serial No. 52,474

4 Claims. (Cl. 254—145)

This invention relates to a jack and while the jack may have various applications, it particularly is designed as a bumper jack for an automobile. It has heretofore been the custom to use jacks which were placed under the axle or spring to elevate the automobile in order to change a tire. It is a difficult and often irksome task to locate such a jack as it must be placed a considerable distance under the car. The present tendency is to use a bumper jack or one which engages the bumper or some part thereof in order to lift the car to change a tire. The bumpers are at the ends of the car and easily accessible and it is not necessary for the operator to get down on the ground and place a jack beneath the car.

It is an object of this invention, therefore, to provide a very simple, easily placed and easily and quickly operated jack for lifting a car by engaging the bumper or bumper support.

It is a further object of the invention to provide a bumper jack having a means for engaging a bumper part, a flexible means secured to said means and a rotatable means for lifting said flexible means and thus raising the bumper and car.

It is a further object of the invention to provide such a jack as set forth in the preceding paragraph in which the rotatable means is operated by a lever-actuated means.

It is still another object of the invention to provide a jack having a base and a frame readily removable therefrom, which frame may comprise spaced members which can be placed at either side of a bumper part and engage the base member.

These and other objects and advantages of the invention will be fully set forth in the following description made in connection with the accompanying drawing, in which like reference characters refer to similar parts throughout the several views and in which:—

Fig. 1 is a view in front elevation of the jack, a portion being broken away and other portions shown in vertical section;

Fig. 2 is a perspective view showing the jack as applied to a bumper support of an automobile;

Fig. 3 is a view in side elevation of the jack;

Fig. 4 is a top plan view, a portion being broken away;

Fig. 5 is a horizontal section on line 5—5 of Fig. 2; and

Fig. 6 is a view in front elevation of a modified form of the device.

Referring to the drawing, a jack is shown comprising a base member 10. While this base member might take various forms, in the embodiment

of the invention illustrated it is shown as comprising a plate of rectangular form in plan, from which plate upstands a pair of cylindrical pins 10a suitably secured to the plate at their lower ends, as by the riveting shown. A frame is shown comprising spaced vertical members 11. Members 11 are shown as tubular and open at their lower ends so that they can be placed over the pins 10a and be supported on the base 10. Members 11 extend a considerable distance above base 10 and at their upper ends are shown as connected by a U-shaped cylindrical bar 12 having its sides disposed in the tops of members 11. A supporting member 13 is provided shown as in the form of a headed and nutted bolt extending through and between members 11. Between members 11 member 13 forms a support or axle for a reel 14 having a comparatively thin circular flange 14a at one end adjacent one member 11 and having a flange at its other end of some width and which is in the form of a ratchet wheel 14b. A flexible cable 15 is provided, one end of which is secured in reel 14 adjacent ratchet wheel 14b and the other end of cable 15 has secured thereto a hook member 16. Hook member 16 is shown as having an aperture through which member 15 passes, the latter being formed into a loop 15a, which loop is maintained by binding wires 17 extending around and clamping the sides thereof. Member 13 has pivoted thereon at one side of ratchet wheel 14b and between the same and the adjacent member 11 a lever 18. Lever 18 has a somewhat elongated slot 18a adjacent its end through which member 13 passes, said lever being of considerable length and extending some distance to one side of member 13, the same being shown as having its outer end somewhat curved downwardly to form a handle. Lever 18 has a pin 19 secured therein and projecting at one side thereof adapted to engage in the spaces between the teeth of ratchet wheel 14b. A pawl member 20 is pivoted on the pivot 21 extending into one member 11, said pawl member extending across and between members 11 in position to seat in one of the spaces between the teeth of ratchet wheel 14b. Pawl 20 is shown as having its free end formed in semi-circular shape and extending about one member 11.

In operation, the base member 10 is placed on the ground beneath the bumper 24 or the bumper-supporting bracket 25 which secures the bumper 24 to the frame 26 of the car. When member 10 is thus placed in position, the frame comprising members 11 is placed in position from above support 25, the members 11 extending at each side of or straddling one side of member 25. The

lower ends of members 11 are placed over or telescoped on the pins 10a and the frame is then supported on base 10. The hook 16 is now hooked under the lower side of member 25. The operator 5 now oscillates lever 18 and on the down stroke engages pin 19 with one of the teeth of ratchet wheel 14b. It will be seen that lever 18 can be drawn outwardly a short distance due to slot 18a so that pin 19 can be disengaged from wheel 14b 10 and lever 18 again lifted to engage said pin with the next adjacent tooth. Wheel 14b is thus intermittently rotated. Pawl 20 is lifted as each tooth of wheel 14b moves thereunder and drops by gravity into the next space. Said pawl therefore prevents reverse movement of wheel 14b. 15 As wheel 14b is rotated reel 14 is rotated and member 15 is wound up on said reel, thus lifting hook 16, bracket 25, bumper 24 and the car body or frame 26. There is quite a distance of lifting capacity and the wheel of the automobile is soon lifted off of the ground so that a tire can be changed. The lever 18 is easily operated and the car is quickly lifted. When it is desired to lower the car it can be let down in gradual stages 20 by pressing down on lever 18 sufficiently to release the tension on pawl 20, then lifting said pawl by hand and holding lever 18 while the car is allowed to descend the distance of one or two teeth on wheel 14b. This operation can be repeated until the wheel is again in contact with the ground. If desired, the car can be quickly lowered by throwing lever 18 upwardly to engage pawl 20 and knock it from engagement with wheel 14b. The weight of the car then quickly pulls 25 down on cable 15, rotating reel 14 so that the car drops at once to the ground.

In Fig. 6 a modified form of the device is shown having a base member 30 comprising a plate of rectangular form and having upstanding centrally therefrom a single pin 30a. A member 31 in the form of a tube open at its lower end is provided and this tube fits over pin 30a. Member 31 has secured to its upper end a frame member 32 illustrated as formed from a flat bar bent into substantially rectangular form with lower side portions 32a extending along each side of member 31 and secured thereto by the rivets 33. A headed and nutted bolt 34 extends through and between the sides of member 32 and has journaled thereon a reel 35 similar in all respects to reel 14 already described and having a ratchet wheel 35a similar to wheel 14b at one side thereof. A lever 36 similar to lever 18 is pivotally mounted on member 34 and has a pin 37 projecting from one side in position to engage ratchet wheel 35a. A small bracket 38 is secured at the upper inner side of member 32 by rivets 39 and a pawl 40 is pivoted to bracket 38 to swing vertically about its pivot 41, the free end of pawl 40 being bent to extend along one side of frame 32. A flexible cable 42 preferably made of wire has one end secured to reel 35 and at its other end has secured thereto a hook member 43 similar to member 16, said hook being secured in a loop 42a formed on the end of member 42.

The operation of the form shown in Fig. 6 is similar to that already described for the device shown in Figs. 1 to 5. Base 30 is placed in proper 70 position beneath the bumper or a supporting part thereof and member 31 is then placed downward over pin 30a. Hook 43 is then engaged with the lower side of the bumper or bumper support and lever 36 is operated as already described in connection with lever 18 to rotate reel 35, wind up

cable 42 and lift hook 43 to lift the bumper and car. The car can be lowered as already described either by gradual steps or by releasing pawl 40 and allowing the car to drop.

From the above description it is seen that 5 applicant has provided a very simple and efficient form of bumper jack. The jack comprises very few parts and can be made of a size which is easily carried under the rear seat of the car or in the trunk now often provided. The jack 10 is very easily and quickly placed in position for operation and the operation is also easy and quite rapid. The speed of operation is one of the important features of applicant's jack. The jack will lift the heaviest cars and the operating lever 15 is operated with remarkable ease. The parts of the jack can be made quite rugged so that the jack will be very durable and yet will not have excessive weight. The device has been amply demonstrated in actual practice and found to be 20 very successful and efficient.

It will, of course, be understood that various changes may be made in the form, details, arrangement and proportions of the parts, without departing from the scope of applicant's invention, 25 which generally stated, consists in a device capable of carrying out the objects above set forth in the parts and combinations of parts disclosed and defined in the appended claims.

What is claimed is:—

30

1. A bumper jack for an automobile having in combination, a plate-like base member adapted to be disposed horizontally on a supporting surface, a frame comprising a pair of spaced parallel adjacent rod-like frame members of small 35 horizontal cross-section extending vertically upward from said base member, the upper part of said frame being separable vertically from and telescoping over the lower part, a reel mounted between the upper ends of said frame members 40 having its axis substantially in the plane passing centrally through said members, a flexible cable secured at one end to said reel and adapted to be wound thereon, a hook secured to the other end of said cable, said hook and the free end of said 45 cable depending between said frame members and closely adjacent the plane thereof, said hook being adapted to engage a bumper part of an automobile, a ratchet wheel secured to said reel, a lever journaled about the axis of said reel, a 50 pawl on said lever for engaging said wheel and rotating the same upon oscillation of said lever and means for preventing reverse rotation of said reel whereby said base member may be placed beneath said bumper, the upper part of said 55 frame moved downwardly straddling said bumper part and engaged with said lower part, said hook engaged with said bumper part and the latter elevated by oscillation of said lever.

2. A bumper jack comprising a base member 60 adapted to be disposed horizontally on a supporting surface, a pair of members upstanding from said base, a pair of standards of small cross-sectional area telescoping over said members and extending upwardly in spaced parallel relation, a reel journaled in said members and disposed therebetween adjacent the top thereof having its axis substantially in the plane passing through the central axes of said members, a ratchet wheel 70 secured to said reel, a lever journaled about the axis of said reel having a pawl engaging said ratchet wheel, a flexible cable secured at one end to said reel and having its free end depending between said standards, a hook adapted to engage 75

a bumper part of an automobile secured to said free end of said cable and means for preventing reverse rotation of said ratchet wheel.

3. A bumper jack for an automobile having in combination, a base member adapted to be disposed horizontally on a supporting surface, spaced members projecting upwardly from said base member, a U-shaped frame having parallel sides, telescoping over said last mentioned members and extending vertically therefrom, a shaft extending through and between said sides, a reel journaled on said shaft, a ratchet wheel secured to said reel, a lever journaled on said shaft, a pawl carried by said lever engaging said ratchet wheel for rotating the same by the oscillation of said lever, a stop pawl pivoted to said frame for preventing reverse rotation of said ratchet wheel, a flexible cable secured at one end to said reel and adapted to be wound thereon having its free end depending between said sides and closely adjacent the plane thereof, a hook secured to said free end adapted to engage a bumper part whereby said base member may be placed beneath said bumper and said U-shaped frame moved downwardly with its sides straddling said bumper part and engaged with said bumper and

said lever oscillated to wind said cable on said reel and lift said bumper part, said cable then extending vertically in a line closely adjacent the center of said base.

4. A bumper jack for an automobile having in combination, a frame comprising a base and an upwardly extending standard of small cross-sectional area, the upper part of said frame being separable from and telescoping over the lower part thereof and having spaced vertically extending portions, a reel axle extending between said portions, a reel mounted on and revoluble about the axis of said axle, a ratchet wheel secured to one end of said reel, a lever journaled about said axle and having a pawl engaging said ratchet wheel, a flexible cable secured at one end to said reel and having a free end depending closely adjacent the plane of said standard, a hook adapted to engage a bumper part secured to said free end and a stop pawl pivoted to said frame extending across said ratchet wheel and across the plane of said lever whereby said lever may be swung upwardly to engage said stop pawl and move the same out of engagement with said ratchet wheel.
